GLOBE SNOW ARRESTOR
Hinman F. Strange, Spotswood Trail,
Gordonsville, Va. 22942
Filed Jan. 23, 1967, Ser. No. 610,957
5 Claims. (Cl. 52—24)

ABSTRACT OF THE DISCLOSURE

This may be defined as a snow arrestor for roofing constructions which is adapted to provide maximum contact of the arrestor per se to snow gathered on roofs. The size of the unit, compared to existing units is substantially the same, the plural snow retaining wires are multiple and present a barricade in depth to the snow, yielding thereby a better means of securing and arresting the snow against falling from the eaves damaging planting and destroying gutters. The arresting of snow in depth permits accumulated snow to melt more gradually than heretofore.

Modifications of invention are adapted to three basic types of roofing, namely slate and/or slate composition; tile and corrugated roofing construction.

More simply stated, an open wire globe is secured to a flat or curved metal bracket, which said bracket is adapted to fit under conventional shingles or tiles or over corrugated roofing. This globe which has the appearance of a bird cage is thus presented perpendicularly to the slope of the roof, approximately several inches above the shingles so as to hold melting snow in depth, in place.

BACKGROUND OF THE INVENTION

(1) Field of the invention

The field of the invention is generally considered to reside in the collection and arresting of sheets of snow accumulated on roof constructions and the like.

(2) Description of the prior art

The best known prior art comprises U.S. patents as follows:

Rogers	97,316
Frank	860,457
Schweda	2,349,201
French	1,215,468

The French and Rogers references are complex expensive arrestors not deemed anticipatory of invention by any extension thereof. The Schweda patent involves the manufacture of a snow guard from wire but the overall configuration and result and concept thereof differ from that of applicant. The French reference, while involving wire, also includes a combination complex tubing; is far more expensive and less efficient than the present invention, especially in that neither French nor the others contemplate the problem of preventing depth engagement of the device to the arrested snow.

SUMMARY OF THE INVENTION

The invention therefore comprises means for securing an oblong globe fabricated of strands of wire to a base member, wherein these units may be set appropriately on a roof and at a pre-selected distance from the eaves for the purpose of arresting snow in depth.

BRIEF DESCRIPTION OF THE DRAWINGS

FIG. 1 shows the basic concept of invention in perspective wherein the snow-arresting globe and its base are secured to sheathing or slate or composition slate;

FIG. 2 is a view in perspective of modification of in-

2

vention in which the snow-arresting globe and base plate are secured to a tile roofing;

FIG. 3 is a view in perspective of invention in which the snow-arresting globe is secured to a base plate designed for exterior contact with a corrugated roofing construction.

DESCRIPTION OF PREFERRED EMBODIMENTS

In FIG. 1, the globe snow arrestor system 100 comprises a base plate 110, which includes a generally flat, preferably rigid shank 112, terminating in a curvilinear end 114, said shank being bent upon itself to form an extension 120, extending generally vertically from the blank 110, and defining plural apertures 122, in the present instance arranged in vertical alignment. Again, with respect to the blank 110, it may be provided with suitable aperture 116, adapted to receive in the event it is secured to roofing sheathing directly, the roofing nails indicated. Otherwise, in practice it is entirely satisfactory for the base plate shank 110, or for its extension 112 to be secured to and between conventional slate or slate composition roofing by any suitable adhesives such as those of rubber derivative, by way of example.

The globe snow arrestor 130 is preferably formed from a single strand of wire, initially coiled and sequentially spread to form a generally spherical globe, but which has impartially "squashed" into the oblong configuration shown. The strands are uniformly spaced between the respective strand-gathering tops 132 and bottoms 134, so as to form an uniform oblong globe of the type shown, and in which the strands, along a circumferential line are each equi-distantly spaced from the other. These strands, each having been formed from a single piece of wire, may be secured at the top 132 by weldment, clamping, tying or any other suitable means, but in the process of manufacture thereof, the portions forming the base of the snow arrestor 130 must be threaded through the respective apertures 122 in such a fashion that the arrestor is secured against displacement upon the application of accumulated snow from above. As indicated, the arrestor is adapted to retard the flow of snow until and upon partially melting it will, by reason of the weight behind and from an upper level, gradually force its melted portions through; but by reason of the configuration a maximum of in-depth contact of the arrestor to the snow is obtained.

The FIG. 2 modification will be apparent from a study of the drawings, wherein it is indicated that the base member 210, corresponding to the base member 110 of FIG. 1 modification, is adapted to rest substantially contiguously to the underside of a ceramic tile or the like, the same being applied in securing relation thereto by suitable adhesive, generally indicated in the fragmentary cut-away portion of the tile. The base plate 210 is of curvilinear configuration as indicated at 214 and extends generally upwardly of the roof-line, although its utility and disposition would be dictated entirely by the roof configuration, per se. The base plate 210 also comprises an upright extension 220 which is bent at a substantially right angle from the blank 210, defining at its upper extension at least two apertures 222. These are suitable for retaining the lower portion of globe 230 in semi-fixed relation to the anchor plate 210. The globe 230 is secured at its top 232 by the means indicated, aforesaid. That is to say, either by weldment, by capping, by crimping, by tying or the like, the respective bottom portions 234 engaging corresponding horizontally disposed apertures 222 as indicated, yielding to the globe a stability against displacement upon the retention and/or arresting of snow within and passage of partially melted-snow from the rear to the foremost portion thereof.

Regarding the FIG. 3 modification, indicated generally by the reference numeral 300, the base plate 310 comprises a blank having an extension 320 cut from the total blank, and a flat portion 312 folded upon the blank, forming thereby an inverted V as indicated. This portion of the base plate or blank 310 is apertured, as is its corresponding portion of the inverted V, permitting passage therethrough of plural securing means (bolts here shown) appearing on both sides and in alignment of the corresponding portions of the base plate. The extension 320 defines, in this instance, three horizontally aligned apertures 322 each being adapted to receive in spaced relation, strand bunches of the globe 330 at its lower portion 334, as indicated. At this juncture, it should be noted that either of the means 322 with respect to FIG. 3, or 222 with respect to FIG. 2, or 122 with respect to FIG. 1, may be used alternately on the respective modifications, depending upon the configuration of the globe desired. That is to say, if it is desired that the base portion of the globe be more spread and portions thereof be horizontally aligned, the means shown in FIG. 3 could be adapted, namely 3 apertures or more in horizontal alignment. By the same token, a less spread globe base of the type 230 can be retained as indicated in FIG. 2, and a globe of substantially more vertically spread characteristics may be secured by the vertically aligned apertures 122 as shown in FIG. 1.

From the aforementioned, it will be apparent that these and other modifications may appear to those skilled in the art without departing from the spirit of the appended claims. The disposition of plural arrestors on any given roof-line is a matter of choice, experience having indicated that a staggered-in-line system is the best.

What is claimed is:

1. A roof adapted snow arrestor comprising:
  - (A) rigid roof-engaging base plate blank, said base plate having an upward extension with a free end;
  - (B) a globular arrestor member anchored at its bottom to the free end of said extension, said arrestor comprising at least one strand of resilient material formed to define an oblate spheroid sieve;

- (C) means securing the base plate to the roof.
- 2. A roof adapted snow arrestor comprising:
  - (A) a rigid roof-engaging base plate blank, said base plate blank having an upward extension with a free end;
  - (B) a globular arrestor member anchored to the free end of said extension, said arrestor comprising at least one strand of resilient material, formed to define a sieve, said strand being turned upon itself to form coils, said coils being joined at top and bottom thereof and intermediately spaced apart, said coils being adapted to compressive anchor engagement with the extension;
  - (C) means securing the base plate to the roof.
- 3. The arrestor of claim 2 in which the arrestor member defines an oblate spheroid.
- 4. The invention of claim 2 in which the arrestor coils defining the arrestor are continuous and each of said strands being passed through at least one base plate aperture which is defined adjacent the upper extremity of said extension.
- 5. The device of claim 4 in which plural strand engaging apertures are horizontally aligned.
